(57) **CLAIM**

The ornamental design for a fiber optic switch, as shown and described.

DESCRIPTION

FIG. 1 is a perspective view of a first embodiment of a fiber optic switch showing our new design;

FIG. 2 is a front elevational view thereof. The rack shown in broken lines forms no part of the claimed design and is shown for illustrative purposes only;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a rear elevational view thereof.
